UNITED STATES PATENT OFFICE.

ALEXANDER DENES, OF BROOKLYN, NEW YORK, ASSIGNOR TO THE WAK NOVELTY CO.,
INC., OF NEW YORK, N. Y.

DOLL-HEAD.

1,309,191.

Specification of Letters Patent. Patented July 8, 1919.

Application filed September 11, 1918. Serial No. 253,620.

To all whom it may concern:

Be it known that I, ALEXANDER DENES, a subject of the King of Hungary, residing at Brooklyn, in the county of Kings and State 5 of New York, have invented new and useful Improvements in Doll-Heads, of which the following is a specification.

This invention relates to dolls, the invention being more particularly related to dolls' 10 heads of the type having movable eye elements.

A main object of the invention is the provision of a construction whereby dolls' heads may be provided with connected eye elements, seated to turn or to open and close automatically, both up and down and to either side, accordingly as the head is tilted into vertical or horizontal position or toward the right or the left.

20 Another object of the invention is the provision of an eye structure which may be quickly and operatively mounted by unskilled or comparatively unskilled workmen, the structure being so made and arranged 25 that it may be introduced and mounted through the neck opening of a one-piece head.

Another object is to provide a device of this character, which is simple in construction, comparatively inexpensive to manufacture, efficient in operation and durable in use.

With the foregoing objects in view and others, the invention resides in the details of 35 construction and in the arrangement and combination of parts hereinafter described, defined in the claims, and illustrated in the accompanying drawings, forming a material part of this specification; and it will be understood that changes and alterations in the 40 precise embodiment of the invention herein described, may be made, to which changes and alterations the inventor is entitled, provided the same are effected within the scope 45 of what is claimed.

In the accompanying drawings:—

Figure 1 is a vertical sectional view through a one-piece doll head in upright position, showing my improved eye structure 50 as applied.

Fig. 2 is a similar view, but showing the relative position of the parts when the head is turned upon its back.

Fig. 3 is a horizontal section of Fig. 1, 55 taken on the line 3—3 thereof, the same

showing my improved eye structure in top plan view.

Fig. 4 is a perspective detail view of the eye structure.

Fig. 5 is a rear elevational detail view, 60 showing an alternate form of one part as applied to the inside of the head, fragmentally and sectionally shown.

Referring more particularly to the accompanying drawings, the numeral 6 denotes a 65 doll's head, cast or otherwise produced in one piece from any suitable substance or composition of matter, the same having a neck opening 7 and on either side of the nose 8, the usual eye-opening or aperture 9, 70 immediately behind which is an eye-ball socket or recess 10.

In order to provide a relatively deep socket, the wall at the forehead region 11 and at the cheek region 12, is made considerably thicker than other parts of the head. 75 On the inside of the head between the sockets 10, in the region corresponding to the nose, there is formed a vertically extending bridge 13, and paralleling the same at the outer 80 sides of the eye-sockets are enlarged regions or walls 14, the same being formed in such manner that the walls defining the sockets in a horizontal or transverse direction, provide circular segments slightly greater than 85 one-half of the eye-balls or globes 15, so that when the latter are pressed into the sockets 10, they may be operatively maintained therein. These enlarged parts may be made or cast integral with the head, or they may 90 be made separately and glued or otherwise secured to the head.

The eye-balls or globes 15 comprise shells made of celluloid or other material, capable of sufficient compression to permit them to 95 be pushed into the eye-sockets, after which they resume their original globular shape, so as to be securely maintained for movement therein. Upon each globe is painted or otherwise provided an iris region 16, normally visualized through the eye aperture 9, and which, accordingly as the globes are turned may be concealed immediately behind the cheek regions 12 or the adjacent regions either to the right or to the left 105 thereof.

Extending centrally through each globe 15 is the end of a wire 17, which, in a position to work in a cavity 18, formed below the enlarged regions, is looped upon itself 110

approximately at right-angles to form an eye 20, the extremity of the inwardly projecting part 21 being bent upon itself to provide a loop or eye 22. Each globe 15 is thus secured to the wire by gluing it thereon or otherwise suitably providing a rigid connection. A link 23, having its opposite ends looped through the eyes 20, pivotally connects the angular wires 17, this link being of such length as to hold the wires spaced-apart at the distance necessary to enable the eye balls 15 to work freely in their sockets. The eye-balls are mounted upon the angular wires in such relation that when the head is in upright position, as illustrated in Fig. 1, the iris regions 16 will be visualized centrally through the eye apertures 9.

Pivotally connecting the looped extremities 22 is a link 24, which carries midway its length a weight 25, by means of which the eye-balls are caused to move accordingly as the head is inclined. Thus, when the head is turned upon its back, as shown in Fig. 2, the weight 25 will drop down, turning the eye balls so as to bring the iris regions behind the cheek parts 12, it being noted that the wires 17 are prolonged through the eyeballs to provide extensions 26, adapted to butt against the inner side of the forehead part 11, and thereby to limit the movement of the eye-balls in this direction. When the head is raised into upright position, or even titled forwardly, the looped portions 19 of the angular wires butt against the inner side of the cheek parts which bound the cavity 18, so as to prevent the iris regions from being carried beyond a central position behind the eye apertures 9. When the head is tilted sideward, the wires 17, forced to turn under the falling movement of the weight, carry the eye-balls in the opposite direction to conceal the iris regions, one behind the bridge 13 and the other behind the cheek part 14, this movement being appropriately limited by the engagement of the looped portion 22 with the adjacent inner side of the head.

In this manner I provide a structure capable of movement both up and down and to either side, accordingly as the head is inclined, so as to produce the effect of open and closed eyes, of eyes oscillating, or of looking directly forward or sidewise. In assembling, the structure is introduced through the neck opening 7 as an entity, and the eyes pressed into their sockets as hereinbefore described. A pair of tongs or any suitably designed tool is employed as means by which to introduce the structure through the neck opening and to press the eyes into their sockets.

In the modified form illustrated in Fig. 5, the head is made without the enlarged regions 14; and the vertical bridge 13 is provided with a groove 27, receptive of the expansive projecting portion 28, formed in-

termidate the length of the spring clip 29, the sides of which are sufficiently curved or bowed outwardly to engage the eye-balls so as to hold them in position for movement as before. When this form is employed, the eye structure is introduced through the neck opening and the eyes seated in their sockets before the application of the spring clip 29, the expansile projecting portion 28 of which is preferably coated or dipped into glue or other adhesive whereby to seal it in the groove 27.

Having thus described my invention, what I claim is:—

1. A doll head provided with eye-ball retaining sockets, eye-balls freely movable in the sockets, a wire engaged with each eye-ball on a central line therethrough and extending downwardly therefrom where it is bent upon itself to provide a laterally projecting portion, connections between the wires, one of which is a weighted connection located between the extremities of the laterally projecting portions, said connections being pivotally engaged and arranged to permit the weighted connection to produce similar turning movements of the eye-balls either up or down or sideward, depending upon how the head is moved or tilted. 90

2. A doll head having eye-sockets flanged by extensions of the material to form segments in the shape of and slightly greater than a hemisphere, elements formed of material adapted to be pressed into said sockets, the same representing eye-balls or globes 100 adapted to move therein in any direction, wire elements fast with said globes or eye-balls centrally therethrough and bent upon themselves therebeneath to provide laterally projecting portions, connections including a weight pivotally arranged between the projecting portions, the same being arranged to produce through the instrumentality of the weight similar movements of the eye-balls either up or down or sideward, depending upon the direction in which the head is moved or inclined. 105

3. A doll head having eye-sockets flanged by extensions of the material to form in one direction segments in the shape of and slightly greater than a hemisphere, elements formed of material adapted to be pressed into said sockets, the same representing eye-balls or globes adapted to move therein in any direction, wire elements engaged with 115 said eye-balls or globes centrally therethrough to provide portions projecting thereabove and portions projecting therebelow, said last portions being looped upon themselves to provide lateral legs projecting interiorly of the head and terminating in loops, a link having its opposite ends pivotally engaged in said first loops connecting said wires, a second link having its opposite ends pivotally engaged in said sec- 120 125 130

ond loops connecting said wires, a weight fast on said second link intermediate its length, said weight being adapted to produce similar movements of the eye-balls either up or down or sideward, depending upon the direction in which the head is moved or tilted, said top wire portions constituting means to abut against an adjacent wall of the head to limit movement in one direction, and the looped regions of said wires being also adapted to abut against adjacent interior parts of the head to limit the movements in other directions.

4. A doll head provided with eye-ball retaining sockets including a bridge element therebetween formed to provide extensions or segments of the sockets in the shape of and slightly greater than hemispheres, elements formed of material adapted to be pressed into said sockets and when therein to comprise eye-balls or globes, angularly formed wire elements having upwardly extending parts engaged centrally through the eye-balls and serving as axes for the same and having also laterally extending parts, a pivotal connection between the wires at their angular regions, a pivotal connection between the laterally extending parts, a weight carried by said last connection, said weight serving as the instrumentality through the connected wires for moving the eye-balls simultaneously, the direction of movement depending upon the direction in which the head itself is moved or tilted.

5. A doll head provided with eye-ball sockets and a grooved bridge-piece therebetween, a spring clip having an intermedi-

ate expansile portion adapted to enter said groove and to be secured thereby and having also outwardly bowed arms, eye-balls 40 adapted to be seated in the sockets and retained for movement in any direction by said bowed arms, wire elements fast with said eye-balls centrally therethrough and bent upon themselves therebeneath at an 45 angle to provide lateral portions projecting toward the interior of the head, connections pivotally arranged between said wire elements, one of which is a weighted connection located at the extremities of the laterally projecting portions, said weighted connection being adapted to serve as the instrumentality by which through the connected wires similarly move the eye-balls 55 either up or down or sideward, depending upon the direction in which the head is moved or tilted.

6. A mechanism for dolls' eyes comprising, in combination, a pair of angular elements, a globe representing an eye-ball 60 mounted centrally upon the upwardly projecting portion of each angular element, a link pivotally connecting the angular elements in the region of the angles thereof, a second link pivotally connecting the extremities of the laterally projecting parts 65 of the angular elements, and a weight fast upon said last link intermediate the length thereof, all substantially as and for the purpose specified.

In testimony whereof I have signed my name to this specification.

ALEXANDER DENES.
